UNITED STATES PATENT OFFICE.

SPEERO POOLEY, OF CHICAGO, ILLINOIS.

CONFECTIONERY-MACHINE.

1,010,174.

Specification of Letters Patent. Patented Nov. 28, 1911.

Application filed July 5, 1910. Serial No. 570,297.

To all whom it may concern:

Be it known that I, SPEERO POOLEY, a citizen of the United States, residing at Chicago, in the county of Cook and State of Illinois, have invented new and useful Improvements in Confectionery-Machines, of which the following is a specification.

This invention relates to confectionery machinery, and has for its object to produce an improved machine for forming confections such as cocoanut biscuits, macaroons and the like.

Another object is to simplify and otherwise improve upon the construction of machines of this class and to such and other ends this invention consists in certain novel features of construction, arrangement and combination of parts, a description of which will be found in the following specification and the essential features will be more definitely pointed out in the claims appended hereto.

The invention is clearly illustrated in the drawings furnished herewith, in which—

Figure 1 is a side elevation of a complete machine embodying my invention, Fig. 1^a is a side view of conveyer actuating eccentric, Fig. 1^b is a side view of a pawl and ratchet mechanism employed in the conveyer actuating mechanism, Fig. 2 is a plan view of the machine, with certain knife lubricating mechanism removed, and certain parts broken out to reveal parts below, Fig. 2^a is a detail cross section taken on the line 2^a—2^a of Fig. 2, Fig. 3 is a detail longitudinal section taken on the line 3—3 of Fig. 2, Fig. 4 is a detail side elevation of a fragment of a head and a cam, Fig. 5 is a side elevation of a fragment of said head, a second cam and a fragment of the press, Fig. 6 is a vertical cross section taken on the line 6—6 of Fig. 1, Fig. 7 is a detail vertical cross section taken on the line 7—7 of Fig. 1, Fig. 8 is a detail side view of a rocker member and locking mechanism, Fig. 9 is a detail view of a second rocking member and pawl and ratchet mechanism for rotating the head, Fig. 10 is a fragmental plan of a die, Fig. 11 is a fragmental plan view of a plunger bar and plungers, and Fig. 12 is a perspective view of a number of the confections made by the machine.

Referring to the drawings, which illustrate the machine in its preferred form, the

main frame of the machine is seen at 11, 55 said frame comprising upright members 11^a, and longitudinally extending members 11^b, connecting said upright members to form a frame of substantial construction. Supported upon this frame are two side frames 12, that carry the operating mechanism for manufacturing the goods. Upon one end of the side frames 12, is supported a press 13, in which the material is placed and said press contains a substantially rectangular chamber 14, in which is slidably mounted a reciprocable plunger 15, operated from a rock shaft 16, by arms 17, secured to the shaft, and links 18, pivotally connected with the outer ends of the arms 17, and with ears 19, upon the rear end of the plunger 15. Arms 20, are secured upon the outer ends of the rock shaft 16, and receive their motion from pitmen 21, which are adjustably secured to said arms and operated by arms 22^b, of rocker members 22, 22^a, rotatively mounted upon a shaft 23, which is journaled in bearings upon the side frames 12. The rocker member 22, has a number of arms for actuating various of the operating members 80 of the machine as will appear more fully later on in this specification. The press has a hopper 24, which opens down into the forward end of the compression chamber 14, and on the upper end of the hopper 24, is 85 journaled a rock shaft 25, which has a blade 26, secured thereto, and adapted to be swung down into the hopper to condense the material therein and to positively force it into the forward end of the compression chamber 90 14. The rock shaft 25, is operated by arms 27, secured upon its end and pivotally connected with pitmen 28, which are pivotally connected with the arms 29, of the rocker members 22, 22^a. The forward end 95 of the press has a transversely extending wall 30, which contains a discharge opening 31, through which the material is fed out into dies, where it is given its shape. A plate 32, is secured upon the outer face of 100 the wall 30, and has a plurality of discharge openings 33, in front of the discharge opening 31 of the wall 30.

The shaft 23, is located in front of the press and has an intermittent rotary movement as will appear later. Said shaft has a head 34, rigidly secured thereon, which head contains the forming dies 36, in which

the material is molded or shaped. In the preferred form, said head comprises two die supporting members 34^a, here shown in the form of circular disks, rigidly secured to the shaft 23, and said disks are slotted radially as at 35, to receive the ends of the dies 36, and plunger carrying bars 37. The dies 36, are formed with a plurality of holes 38, of substantially the same size and shape as the discharge openings of the plate 32, which holes are brought to register with said discharge openings in the operation of the press. As shown in the drawings, four of these dies are provided on the head 34, and each die has lugs 39, which project into the slots 35, of the disks and is guided to move longitudinally therein. The plunger carrying bars 37, are provided with plungers 40, that normally project part way into the holes 38, of the dies and said plunger carrying bars are also provided with lugs 41, upon their ends which extend into the slots 35, of the disks. Said plunger carrying bars are mounted upon adjustment screws 42, that are rotatively mounted in struts 43, 44, extending across the slots 35, and said screws are provided with shouldered portions 45, 46, that abut against the struts 43, and against the bottoms of sockets 46^a, in the struts 44. Said adjustment screws are threaded as at 47, and engage with internally screw threaded holes in the lugs 41. It is evident that by rotating the adjustment screws, the plunger carrying bars may be adjusted toward or away from the center of the rotating head to bring the outer or end faces of the plungers at the desired points within the openings of the dies, so as to increase or decrease the depth of the sockets formed between the walls of said openings and the end faces of the plungers, thus determining the size and shape of the confections molded or shaped by the dies. Between the lugs 39, 41, are interposed springs 48, which hold the dies in their outward position to receive the material from the press whenever they are brought into register therewith. Secured upon the inner sides of the frame like members 12, are two cams 49, which have cam faces 50, that are arranged to move the dies 36, back upon the plungers to discharge the confections from the dies and the latter are provided with rollers 51, upon their ends, which rollers run upon the cam faces 50, and onto concentric faces 52,—that is to say, faces that are concentric with the axis of rotation of the shaft 23—where they remain during the interval that the rotating head is stationary. The cam faces 50, are so shaped and arranged that each die will be forced back sufficiently to expose the end faces of the plungers therein, thereby exposing the confections which have been contained in the die. A stripping device 52^a, extends transversely

across beneath the lowermost die and plungers and acts to remove the confections from the plungers in case they should stick upon them after the die has been forced back. As shown said stripping device comprises a piece of wire extending between the cams 49, and arranged immediately under the concentric faces 52, thereof, so that after the dies have been moved back to expose the confections, the wire will be in position to remove them. 70 75

Adjacent to the discharge plate 32, are two cams 49^a, for retracting the dies, as they move by said plate, so that the corners of the dies will not strike said plate. Said cams have inclined faces 50^a, with which the rollers 51, contact and are forced back sufficiently so that the corners of the dies will clear the discharge plate. Recesses 50^b, are provided in the cams 49^a, into which the rollers move as the head comes to a position of rest, whereby the dies may be forced into contact with the discharge plate by the springs, 48. 80 85

At some point between the discharge openings of the press and the point where the confections are stripped from the dies, is a roller or other smoothing device 54, which contacts with the outward faces of the dies and rolls upon the exposed sides of the confections to smooth the exposed surfaces thereof. This roller is movably mounted, and as here shown is carried by arms 55, that are pivoted upon the side frames 12, and yieldingly pressed toward the rotating head by springs 56, a stop 57, being provided to limit the movement of the roller toward the head. It is obvious that as the die passes by the roller, the latter will follow the outer face thereof and press against the exposed side of the material contained in the die. 90 95 100 105

Mechanism is provided for severing the material, which has been forced into the die, from the stock in the press, and as shown said mechanism comprises a vertically reciprocable knife 58, carried by a cross-bar 59, which is secured upon the upper ends of the vertically reciprocable posts 60, that are slidably mounted in guides 61, secured to the side frames 12. The posts 60, receive their reciprocatory movements from a pair of eccentrics 62, fast upon the main drive shaft A, and connected with the posts by pitmen 63. The knife 58, extends across all of the discharge openings 33, and the mechanism is so timed that the knife moves down to sever the material after the latter has been forced into the holes of the die which is in register with the plate 32, and before the rotatable head begins to move to its next position. It is found highly desirable to lubricate the knife so that the material will not stick thereto, and with this object in view I have provided a number of spraying nozzles 64, 110 115 120 125 130

upon a header 65, that is connected to a suitable source of water supply. The nozzles have projecting valve stems 66, which are arranged in the path of travel of the 5 knife carrying bar 59, and open the nozzles whenever struck by said bar 59. In this manner the knife is lubricated each time that it operates to sever the material.

The rotatable head 34, receives its intermittent rotary motion from the rocker member 22^a, which has a spring actuated pawl 66^a, pivotally secured thereto and arranged to engage with the teeth of a ratchet 67, rigidly secured to the shaft 23. There are as 15 many teeth upon the ratchet 67, as there are dies upon the head, and the rocker member is given one forward and backward movement for each cycle of operation of the machine. Both rocker members 22, 22^a, receive this motion from eccentrics 68, fast 20 on the shaft A, being connected to said eccentrics by pitmen 69, that extend from arms 70, of the rocker members.

Means are provided for positively holding the rotatable head stationary during its 25 periods of rest and as shown said means comprises a latch 71, secured to one of the side frames 12, and having a bolt 73, adapted to project into any one of the holes 72, in 30 a collar 72, fast upon the shaft 23. The bolt 73, of the latch is pressed toward the collar 72, by a spring 74, and remains in engagement with one of the holes in the collar during such period of time as the head 35 is to remain at rest. A cam block 75, is carried by the rocker member 22, and engages with a pin 76, upon the bolt of the latch to withdraw it from its engagement with the collar at such time as the pawl 66^a, 40 picks up the ratchet 67. In this way the rotatable head is positively held in a stationary condition during its period of rest and is unlatched just in time to be moved to its next position.

45 Mechanism is provided for lubricating the sockets in the dies and as shown said mechanism comprises a number of nozzles 77, that open out from a header 78, which receives its water supply through a flexible connection 79. The header is slidably mounted in ways 80, that are carried by the side frames 12, and said header carries a shaft 81, which is connected to rocker arms 82, by links 83. The rocker arms are secured upon a rock 50 shaft 84, journaled in bearings upon the side frames 12, and receive their rocking movement from the rocker members 22, 22^a, through links 85, that are pivotally connected to the rocker arms 82, and to arms 86, of 55 said rocker members 22, 22^a. Said nozzles have projecting valve stems which strike the bottoms of the sockets in the dies as they are brought in front of the nozzles, the inward movement of the stems operating to 60 open the nozzles. The arrangement of the 65

parts is such that the nozzles are brought forward and into contact with the end faces of the plungers during a portion of the interval that the rotatable head is stationary, and are retracted while the head is being 70 turned to its next position.

Below the operating parts of the machine is a conveyer adapted to support and convey the baking pans or boards underneath the head. As shown in the drawings, said 75 conveyer comprises a pair of chains 87, which travel over sprockets 88, fast upon shafts 89, 89^a, journaled in bearings upon the ends of two rails 90. Said rails are secured upon the inner sides of the frame 11, 80 and the upper bights of the chains 87, travel upon said rails. At suitable intervals the links of the chain are provided with laterally extending lugs 91, which are adapted to propel the baking pans or boards B, that are 85 placed upon the chains as shown at Fig. 3. The chains are driven by an eccentric 92, upon the shaft A, which eccentric is connected to an arm 93, loose on the shaft 89^a, by a rod 94. The arm 93, carries a 90 pawl 95, which co-operates with a ratchet wheel 96, fast upon the shaft 89^a, to partially rotate the same when the arm 93, is moved in one direction. The arrangement 95 of the parts is such that the conveyer will be moved a distance somewhat greater than the length of the confections made in the die, once during each cycle of the machine.

It is desirable to sprinkle the pans or boards B, with some substance, as for instance powdered sugar, and to sprinkle the upper surfaces of the confections with the same substance after they have been deposited upon the said pans or boards, and with this object in view I have provided a 100 pair of shaking or vibrating sieves 97, 98, which are supported from the side frames 12, by links 99. Said shaking sieves may be given a shaking motion to discharge the 105 finely powdered sugar, by any suitable mechanism, here shown as comprising toothed segments 100, fast upon the rock shafts 16, 94, respectively, and engaging with lugs 101, upon the sieves. It is obvious that as the shafts turn, the teeth of the 110 segment will force the lugs back and move the sieves forward and that by providing springs 102, between the links 99, and frame, the sieves will be forced in the opposite direction.

115 Whenever the machine is driven from a high-speed power shaft, it is desirable to speed the machine down somewhat and in order to accomplish this I have provided 120 gearing between the shaft A, and the power shaft, which as shown, comprises a gear wheel 103, upon the shaft A, a pinion 104 fast upon a shaft 105, journaled in bearings upon the frame of the machine, a gear wheel 106 fast upon said shaft 105, and meshing 125

with a pinion 107, fast upon a shaft 108, journaled in bearings upon the frame 11. The shaft 108, bears tight and loose pulleys 109, 110.

5 In the operation of a machine, the material is fed into the hopper 24, and said material is compressed and fed forward by the plunger 15, forced through the discharge openings in the plate 32, and into 10 the sockets in the dies 36. The parts are so timed that the head will be stationary as the material is being forced into the sockets in the die that registers with the plate 32. At about the same time, the knife 15 has been moved to its uppermost position, thereby causing the nozzles 64, to spray the knife, and the stems of the nozzles 77, have 20 been brought forward into engagement with the plungers in front of them to spray the sockets in the die. It is obvious that while the plunger 15, and nozzles 77, are moving that the shaking sieves 97, 98, will be agitated to sprinkle the baking pans or boards and the completed confections. When the 25 plunger 15, has reached its limit of compressing movement, and begins its return movement, the knife is brought down, thereby severing the material in the full die from the remainder in the press, after which the 30 pawl 66^a, on the rocker member 22^a, strikes a tooth on the ratchet 67, and turns the head one fourth way around, thereby bringing the full die down to its lowermost position. As said die leaves its position in front of 35 the plate 32, it is forced back slightly by the cams 49^a, and as it passes by the roller 54, said roller smooths down any uneven places on the exposed side of the confections contained in said die. Just before coming to 40 its position of rest, the die is forced back sufficiently by the cam 49, to completely expose the confections, which engage with the stripping device 52, and are thereby positively removed from the plungers. The 45 conveyer is shifted by the eccentric 92, and the pawl and ratchet mechanism 95, 96, to move the confections deposited on the baking board or pan out of the way of the next batch. While the confections are being 50 discharged from the lowermost die, another die has been brought into register with the discharge openings of the press and is being filled with material, and the operation just described is again gone through. It is ob- 55 vious that the discharge end of the conveyer may run to or through or over a baking oven or other heating device by simply extending said rails sufficiently and placing a gas plate or other heating apparatus 60 about it.

It is obvious that in place of the dies shown in the drawing, other dies may be substituted therefor having holes of different contours, so that a variety of shapes may 65 be given the confections. In Fig. 12 *a*, rep-

resents a confection made in dies like those shown in the drawings, while *b*, *c*, represent confections made from dies having holes corresponding in shape to said confections.

I am aware that various alterations and modifications of this device are possible without departing from the spirit of my invention, and I do not therefore desire to limit myself to the exact form and construction shown and described. 75

I claim as new and desire to secure by Letters Patent:

1. In a confectionery machine, the combination with a suitably operated press having a plurality of discharge openings, of an intermittently rotated head, comprising die carrying disks, dies mounted upon said disks and capable of being moved radially thereof, said dies having holes adapted to be 80 brought into register with the discharge openings of the press, plunger carrying bars supported by said disks and plungers upon said bars, extending into the holes in the dies, stationary die-moving cams, and 85 rollers secured to the dies and adapted to engage with said cams; substantially as and for the purpose set forth.

2. In a confectionery machine, the combination with a suitably operated press having a plurality of discharge openings, of an intermittently rotated head, comprising two die carrying disks having radial slots therein, dies having holes adapted to be brought 90 into register with the discharge openings of the press and being provided with lugs upon their ends traveling in the slots of said disks, plunger carrying bars having plungers extending into the holes in the dies and being provided with lugs guided in the slots in the 95 disks, adjustment screws journaled in said disks and being threaded in the lugs of the plunger carrying bars, and stationary cams adapted to coöperate with rollers upon the ends of the dies, to move said dies inwardly 100 to discharge the contents thereof. 105

3. In a confectionery machine, the combination with a pair of circular die carrying disks having a plurality of radial slots therein, and struts extending across said slots, of 110 dies guided to move radially in said slots, plunger carrying bars guided to move radially in said slots and having plungers extending into holes in the dies, adjustment screws journaled in said struts and being 115 threaded in the ends of said plunger carrying bars, and springs interposed between the dies and plunger carrying bars; substantially as and for the purpose set forth.

4. In a confectionery machine, the combination with a suitably operated press having a plurality of discharge openings, and an intermittently rotated head having a plurality of dies provided with holes adapted to be brought into register with the discharge 120 125

openings of the press, of a vertically reciprocable knife moving between the discharge end of said press and the die in register therewith, and a plurality of spraying nozzles having valve stems lying in the path of the knife and adapted to be actuated thereby.

5. In a confectionery machine, the combination with an intermittently rotated die carrying head, of a plurality of spraying nozzles having valve stems projecting beyond the ends of the nozzles, a header carrying said nozzles and adapted to be connected with a suitable water supply, and mechanism for reciprocating said header to bring 10 the valve stems of the nozzles into engagement with the die carrying head.

6. In a confectionery machine, the combination with an intermittently rotated die carrying head, of a plurality of spraying nozzles having valve stems projecting beyond the ends of the nozzles, a header carrying said nozzles and adapted to be connected with a suitable water supply, a rock shaft, arms upon said rock shaft, connections between 20 said arms and header, and mechanism for rocking said arms to bring the valve stems into contact with the dies while the head is in a stationary position.

7. In a confectionery machine, the combination with an intermittently moving conveyer, of an intermittently rotated confection forming head arranged to deposit confections upon said conveyer, and moving in unison with said conveyer, a reciprocable 35 member, moving toward and away from said head, a shaking sieve located above said conveyer, and mechanism, operatively connected with said reciprocable member, for vibrating said sieve.

40 8. In a confectionery machine, the combination with a press having a plurality of discharge openings, of an intermittently rotated die carrying head having dies adapted to be brought into register with the discharge 45 openings of the press, a collar having opposing shoulders and rigidly connected with said head, a spring pressed bolt adapted for engagement with said opposing shoulders of the collar to lock the head against movement in either direction during its in-

terval of rest, and movable means for disconnecting the bolt from the collar.

9. In a confectionery machine, the combination with a press having a plurality of discharge openings, of a rock shaft, a die 55 carrying head secured thereon, and having perforated dies adapted to be brought successively into register with said discharge openings, a rocker member carried by said shaft, a pawl and ratchet connection between 60 said rocker member and shaft, a second rocker member carried by said rock shaft, a collar having a plurality of pairs of opposing shoulders, said collar being secured upon said rock shaft, a spring bolt adapted 65 to seat between any pair of shoulders in the collar for locking the rock shaft against movement during its interval of rest, a cam block carried by said second named rocker member and adapted to disengage the bolt 70 from the collar when the pawl picks up the ratchet, and mechanism for rocking both of said rocker members.

10. In a confectionery machine the combination with a rotating drive shaft, a rock 75 shaft and connecting mechanism between said shafts for transforming the rotating movement of said rotating shaft into a rocking movement of said rock shaft, including a rocker member having four arms, one of 80 which is connected to said motion transmitting mechanism, a die carrying head carried by said shaft, a press for feeding material into the dies of the head, a plunger in said press and operated from one of the arms on 85 the rocker member, a condensing blade for condensing the material in the press and operated from one arm on the rocker member, a knife for cutting off the fed material and operated from one of the arms on said rocker 90 member, and a spraying device for spraying the dies operated from another arm on said rocker member.

In witness whereof I have hereunto subscribed my name at Chicago, Cook county, 95 Illinois, this 2nd day of July, 1910.

SPEERO POOLEY.
